UNITED STATES PATENT OFFICE.

JOSEPH P. KENNEDY, OF CHICAGO, ILLINOIS.

BASKET-BALL GOAL.

1,193,024.

Specification of Letters Patent.

Patented Aug. 1, 1916.

Application filed May 19, 1916. Serial No. 98,500.

To all whom it may concern:

Be it known that I, JOSEPH P. KENNEDY, a citizen of the United States, residing at Chicago, in the county of Cook and State of Illinois, have invented certain new and useful Improvements in Basket-Ball Goals, of which the following is a specification.

My invention relates to a goal for basket ball, or other similar game, and the principal 10 object of the invention is to provide a structure for this purpose which will be strong and sufficiently resilient so that it will not be readily bent out of shape by the ball striking against it.

15 A further object is to provide a device of this sort which will be inexpensive to manufacture and slight in appearance, and so constructed with reference to its attachment to the backboard that the ball cannot lodge 20 or become caught between a part of the goal and the backboard.

The invention is illustrated in certain preferred embodiments in the accompanying drawing, in which—

25 Figure 1 is a view, in perspective, of a goal cast in one piece shown as attached to the backboard or other support; Fig. 2, a plan view of the same; Fig. 3, a side elevation thereof; Fig. 4, a fragmentary plan view, with the backboard shown in section, of a modified form of the invention; Fig. 5, a sectional view on line 5—5 of Fig. 4 showing the goal ring in elevation; and Fig. 6, a detail sectional view on line 6—6 of Fig. 4.

25 Like characters of reference designate like parts in the several figures of the drawings.

The embodiment of the invention shown in Figs. 1, 2 and 3 is composed preferably of a single malleable iron casting, although, 40 if desired, the ring might be made separately from the attaching bracket. The device comprises an attaching plate A which may be secured or otherwise fastened to the backboard or other supporting structure B. The 45 plate is formed with outstanding vertical webs C which are reinforced by oblique transversely arranged webs D, E, the plate and webs forming together a supporting bracket for the ring F. This is made in- 50 integral, preferably, with the rest of the de- vice. The ring is thickest at the place where it is united with the supporting bracket. From this place its thickness gradually di- 55 minishes to the point diametrically opposite the bracket. This construction gives the ring strength and at the same time it is

comparatively resilient, as a result of which it will bend when struck by the ball but will spring back to its original shape. A tapered ring has this capacity of springing back to 60 its original form when bent, whereas a ring of uniform thickness will often take a permanent set when subjected to the same strain. The device is constructed so that it affords no place for the ball to lodge. The 65 width of the supporting bracket is such that the ball, a portion of the outline of which is indicated at G, will touch the backboard at one point and the ring at another without coming into contact with the webs forming 70 the supporting bracket. The ball cannot lodge on the device at any point or become caught between it and the backboard. With the goals heretofore used in the game of basket ball, the ball frequently is caught or 75 wedged between some part of the device and the backboard, which necessitates stopping the play and starting again with the ball in the middle of the field.

In the device shown in Figs. 4, 5 and 6 80 the goal ring H is preferably of steel forg- ing. It is less than a complete circle and the extremities J fit into sockets K formed on the supporting bracket L. The sockets are slotted at M and formed with lugs N 85 which are drawn together by screw bolts O to clamp the ends of the goal ring to the bracket. The bracket is formed with an arcuate rib or web P having the same radius and struck from the same center as the mem- 90 ber H.

I claim:

1. A basket ball goal comprising a ring and means for attaching the same to a wall or other structure, the ring being relatively 95 thin at the point remote from the place of attachment and gradually increasing in thickness toward such place of attachment.

2. A basket ball goal comprising a cast malleable iron ring and means for attach- 100 ing the same to a wall or other structure, the ring being relatively thin at the point remote from the place of attachment and gradually increasing in thickness toward such place of attachment.

3. A basket ball goal consisting of a cast- 105 ing in the form of a ring and an attaching bracket integral with the ring, the ring hav- ing its greatest thickness at the place where it joins the bracket and gradually diminish- 110 ing in thickness toward the point diametri- cally opposite thereto.

4. A basket ball goal consisting of a casting in the form of a ring substantially circular in cross section, and an attaching bracket integral with the ring, the ring having its greatest thickness at the place where it joins the bracket and gradually diminishing in thickness toward the point diametrically opposite thereto.
5. A basket ball goal comprising an attaching plate formed with webs projecting from one side thereof and a ring integral with said webs, the thickness of which is greatest at the place adjacent the webs and gradually diminishing toward a point diametrically opposite thereto.
6. A basket ball goal comprising an attaching plate formed with webs projecting from one side thereof and a ring integral with said webs, the thickness of which is greatest at the place adjacent the webs and
7. A basket ball goal comprising a ring and means for attaching the same to a wall or other structure, the ring being substantially circular in cross section and relatively thin at the point remote from the place of attachment and gradually increasing in thickness toward such place of attachment.
8. A basket ball goal comprising an arcuate goal member and a supporting bracket to which the ends of said member are secured, said bracket being formed with an arcuate web of the same radius and struck from the same center as said goal member so that said goal member and web form together a complete circle.

JOSEPH P. KENNEDY.
